UNITED STATES PATENT OFFICE

WILLIAM H. MINER, OF CHAZY, NEW YORK, ASSIGNOR TO W. H. MINER, INC., OF CHICAGO, ILLINOIS, A CORPORATION OF DELAWARE

CAR CONSTRUCTION

Application filed March 8, 1928. Serial No. 260,025.

This invention relates to improvements in car construction.

In the operation of railway passenger cars, it is highly desirable that means be provided to prevent separation of the body and truck bolsters in the event of a collision, in order to eliminate or minimize danger of telescoping of the cars. With the types of bolster locking pins heretofore provided for the above purpose, much difficulty has been encountered in the use thereof on certain classes of cars, particularly dining cars. As well known, most passenger cars employ six-wheel trucks, the center axle of which is directly located below and adjacent the center pin, so that it becomes either impossible or exceedingly difficult to insert or remove the bolster locking pin from the under side of the bolsters whenever it becomes necessary to remove the car body from the trucks in making repairs. This difficulty has been partially overcome by inserting the locking pin through the floor of the car from above the bolsters, but this expedient is unsatisfactory, especially in the case of dining cars. In dining cars, the heavy kitchen range is almost universally located directly over the centers of one set of bolsters, and consequently, when necessary to separate the car body from the trucks, it has heretofore been necessary to first remove the kitchen range. Obviously this involves much labor, expense and delay in carrying out the desired repairs.

One object of my invention is to provide a bolster locking center pin, especially adapted for those cars where the pin cannot conveniently be inserted or removed from the under sides of the bolsters and which improved pin will readily permit separation of the body and truck bolsters without the necessity of obtaining access to either the upper side of the body bolster or the under side of the truck bolster after the pin has once been applied.

Another object of my invention is to provide a bolster locking center pin which may be rendered ineffective temporarily by merely withdrawing removable locking means associated therewith, which removable means

may be withdrawn laterally and which is accessible at one side of the bolster.

Other objects of the invention will more clearly appear from the description and claims hereinafter following.

In the drawing forming a part of this specification, Figure 1 is a vertical sectional view taken diametrically of the center bearing portions of the body and truck bolsters of a passenger car and showing my improvements in connection therewith, certain of the parts being broken away in order to better accommodate the figure on the drawing. And Figure 2 is a horizontal sectional view, corresponding to the line 2-2 of Figure 1.

In said drawing, A indicates, broadly, a body bolster of a passenger car, and B a truck bolster, the latter being generally in the form of a spider, but the details of which are unnecessary of illustration or description in connection with my invention, inasmuch as the details of the bolsters may vary, as will be obvious. The improved locking center pin comprises two elements C and D and a retaining key E, the details of which will be herein-after set forth.

The body bolster A is, or may be, of any well known construction, and, as shown, is formed with a vertical elongated hub section 10 having a vertically extending, cylindrical opening 11 for the reception of the center pin. At the upper end of said opening 11, the body bolster is provided with a rectangular horizontal shoulder 12 and the opening upwardly thereof is of similar cross section, as indicated at 13. A portion of the car floor is indicated at 14, between which and the top of the body bolster A is an annular collar or sleeve 15, through which the upper element C of the center pin may be entered from above, the floor opening being closed by any suitable means, such as the cover plate 16.

The body bolster A is preferably formed with an integral center bearing plate section 17 co-operable with a preferably detachable center bearing plate 18, the latter being mounted on the truck bolster B and confined in proper position by sections 19-19 of the truck bolster. The center plate section 17 is shown as formed with a female recess 20 in

which is entered the male section 21 of the center bearing plate 18.

The truck bolster B is formed with an upper horizontal web 22 having a center pin opening 23, at the bottom of which is provided an annular shoulder 24. The truck bolster also has vertical web sections 25 below the center pin opening and to which is adapted to be secured, as by rivets 26, a sustaining plate 27.

The center pin proper is preferably comprised of two substantially like sections C and D. Each of said sections is formed with a head of sufficient diameter to prevent passage through the center pin openings in the bolsters. The head 28 of the section C is preferably square and the head 128 of the section D is preferably of annular form. At one side of the head, each section is provided with a cylindrical stem 29 conforming to the diameter of the center pin opening. Each cylindrical section 29 is cut away on an ogee curved surface 30, as clearly shown in Figure 1, the ogee curved surfaces being complementary, so that when the two pin sections C and D are assembled, as shown in Figure 1, said surfaces 30 will meet and thus provide a center pin of full and continuous cylindrical form from top to bottom. The upper section C may be provided with a flange 31 on the upper end thereof, which flange may be suitably apertured so as to receive a hook or the like, for withdrawing the pin upwardly should this become necessary. As will be clear from the drawing, the head 28 of the upper section C normally rests on the shoulder 12, said section C being entered from the top and the head 128 of the lower section D normally rests upon the supporting plate 27, or at least is prevented from falling out thereby. Any tendency to separate the bolsters vertically will result in the head 128 of the lower section D engaging with the annular shoulder 24, as will be obvious.

The pin sections C and D are provided with aligned transversely extending openings 32, which are also aligned with transversely extending openings 33—33 provided in the side walls of the hub section 10 of the body bolster. The retaining key E is entered through the aligned openings 32 and 33, as shown in the drawing, and is held against accidental removal by any suitable means, such as cotters 34—34, entered through the key E on opposite sides of the hub section 10. Said key E is preferably in the form of a relatively heavy bar of rectangular cross section, with the widest dimension extending vertically or parallel to the axis of the center pin so as to thereby obtain the maximum strength of the key against shear when there is any tendency of the bolsters to separate vertically. For convenience, the key E may have a suitable hand-hole 35 at its end to facilitate insertion and removal.

In actual practice, when the car is built and the body assembled with the truck, the pin section C will be entered through the floor of the car and the cover plate 16 put in place. Similarly, the pin section D will be entered from the under side of the truck bolster B and, when in place, the retaining plate 27 will be applied and the attachment thereof may be made permanent. With the two pin sections C and D associated with the body and truck bolsters, respectively, it is evident that the car body may be lowered upon the truck and the two pin sections will be thereby assembled. When assembled, the key E is inserted, thus obtaining the desired locking effect between the body and truck bolsters and preventing vertical separation thereof, in the event of collision or other accident. Should it be desired to separate the car body from the truck bolster at any time, to effect repairs, it is only necessary to withdraw the key E, leaving the pin sections C and D associated with their respective bolsters A and B.

By employing a square head 28 on the pin section C and a correspondingly shaped recess to receive it, the position of the pin section with respect to the body bolster is maintained and turning prevented, thus insuring alignment of the key receiving openings of the bolster and said pin sections. Due to the ogee engaging surfaces of the two pin sections, the section D will also be positively positioned to maintain its key opening 32 in alignment with the openings 33.

With the arrangement shown and described, it is evident that I overcome the difficulties and disadvantages inherent in former types of center locking pins, particularly where such pins are used on passenger equipment, such as sleeping cars and dining cars. The arrangement is such that no special designs of bolsters are required and the locking center pin may also be manufactured at comparatively small expense.

Although I have herein shown and described what I consider the preferred manner of carrying out my invention, the same is merely illustrative and I contemplate all changes and modifications which come within the scope of the claims appended hereto.

I claim:

1. In car construction, the combination with body and truck bolsters having aligned center pin openings; of a shouldered pin extended within said openings, the shoulder thereof being adapted to co-operate with a shouldered portion on one of said bolsters to prevent separation of said pin therefrom in one direction; and a one piece laterally removable element extending through the pin and opposed walls of the opening of the other bolster and having shouldered engagement with said pin and said last named bolster, whereby to prevent separation between said pin and said other bolster.

2. In car construction, the combination with body and truck bolsters having aligned center pin openings; of a shouldered pin extending within said openings, the shoulder thereof being adapted to co-operate with a shouldered portion on the truck bolster to prevent separation of said pin therefrom in one direction; and laterally removable locking key extending entirely through the pin and the opposed walls of the opening of the body bolster and having shouldered engagement with said pin and the body bolster, whereby to prevent separation between said pin and said body bolster. 70
- 5 3. In car construction, the combination with body and truck bolsters having aligned center pin openings; of a headed pin extended through the truck bolster and having the shank thereof extended within the body bolster, the head of said pin limiting the upward movement of the pin with respect to the truck bolster; means secured to the truck bolster engageable with said pin, adapted to prevent the latter from falling down; and transversely removable means having shouldered engagement with the body bolster and said pin, to prevent relative vertical separation of said pin and body bolster. 80
- 10 4. In car construction, the combination with body and truck bolsters having aligned center pin openings; of a headed pin extended through the truck bolster and having the shank thereof extended within the body bolster, the head of said pin limiting the upward movement of the pin with respect to the truck bolster; means secured to the truck bolster engageable with said pin, adapted to prevent the latter from falling down; and transversely removable means having shouldered engagement with the body bolster and said pin, to prevent relative vertical separation of said pin and body bolster. 85
- 15 5. In car construction, the combination with body and truck bolsters having aligned center pin openings; of a headed pin extended through the truck bolster and having the shank thereof extended within the body bolster, the head of said pin limiting the upward movement of the pin with respect to the truck bolster; means secured to the truck bolster engageable with said pin, adapted to prevent the latter from falling down; and transversely removable means having shouldered engagement with the body bolster and said pin, to prevent relative vertical separation of said pin and body bolster. 90
- 20 6. In car construction, the combination with body and truck bolsters having aligned center pin openings, each bolster having an annular shoulder adjacent its corresponding end of the center pin opening; a two-section center pin, each section being entered through an opening of one of the bolsters, 95
- 25 7. In car construction, a body bolster having a center pin opening and a shoulder at the top end of said opening; of a truck bolster having a center pin opening and a shoulder at the lower end of said opening; a center pin element shouldered at its upper end and adapted to co-operate with the body bolster shoulder and having the shank extending into the center pin opening; a second center pin element having a shouldered end adapted to co-operate with the shoulder of the truck bolster and having its shank entered within the center pin opening, said shanks overlapping; and laterally removable means having shouldered engagement with each of said pin sections and one of the bolsters. 100
- 30 8. In car construction, a body bolster having a center pin opening and a shoulder at the top end of said opening; of a truck bolster having a center pin opening and a shoulder at the lower end of said opening; a center pin element shouldered at its upper end and adapted to co-operate with the body bolster shoulder and having the shank extending into the center pin opening; a second center pin element having a shouldered end adapted to co-operate with the shoulder of the truck bolster and having its shank entered within the center pin opening, said shanks overlapping; and laterally removable means having shouldered engagement with each of said pin sections and one of the bolsters, said means comprising a key extended through aligned openings in said shanks and in the body bolster. 105
- 35 9. In car construction, the combination with body and truck bolsters having aligned center pin openings; of a pin extended within said openings, said pin having shouldered engagement with one of the bolsters to prevent removal of the pin therefrom in one direction; and means extending through the pin and opposed walls of the opening in the other bolster to prevent separation between said pin and said other bolster, said means being bodily removable in a lateral direction to permit separation of said bolsters. 110
- 40 10. In witness that I claim the foregoing I have hereunto subscribed my name this 6th day of March, 1928. 120
